UNITED STATES PATENT OFFICE.

ARTHUR THOMAS WOODWARD, OF BENDIGO, VICTORIA.

UMBRELLA-HOLDER FOR CYCLES.

SPECIFICATION forming part of Letters Patent No. 604,674, dated May 24, 1898.

Application filed December 1, 1896. Serial No. 614,125. (No model.)

To all whom it may concern:

Be it known that I, ARTHUR THOMAS WOODWARD, artist, a subject of the Queen of Great Britain and Ireland, and a resident of Water-
loo place, in the city of Bendigo, county of
Bendigo, and Colony of Victoria, have in-
vented a certain new and useful Umbrella-
Holder for Cycles, of which the following is a
specification.

10 The object of my invention is to provide an
attachment to bicycles, tricycles, and similar
vehicles whereby the riders of the same are
protected from the effects of either sun or
rain.

15 It consists in certain novel constructions,
combinations, and arrangements of parts,
as will be hereinafter fully described and
claimed.

Referring to the drawings which form a
20 part of this specification, Figure 1 represents
a side elevation of the attachment complete,
showing its connection to the saddle-pillar
tube and the means by which the umbrella
and its telescopic rod are attached. Fig. 2
25 shows, on an enlarged scale, and in two illus-
trations, a front elevation of the joint be-
tween the umbrella-rod and the umbrella-rod
end as shown in Fig. 1. In the upper illus-
tration one of the sides of the fork (the
30 grooved side) on the end of the umbrella-rod
has for the convenience of illustration been
removed, exposing the tongue and the ridge
thereon. In the lower illustration is seen the
inside face of the removed side. This side
35 may either be loosely riveted or hinged or in
other ways attached to the plug secured in
the end of the umbrella-rod, and on it are
seen at various angles the grooves into which
the ridge shown in the upper illustration may
40 fit. Fig. 3 represents an end elevation of the
umbrella-rod, showing the screw by which
the fork and tongue are locked together.
Fig. 4 shows a fancy handle which can be at-
tached to a specially-constructed umbrella-
45 rod for the convenience of the cyclist when it
is required to use the umbrella but not the
machine. Fig. 5 represents a plan of the clip
which surrounds the saddle-pillar tube,
though I do not bind myself to this special
50 form of clip, since it may be of any shape con-
sistent with adjustability. Fig. 6 shows a

side elevation of a lady's machine with the
whole attachment complete and in position.

Similar letters of reference indicate similar
or corresponding parts where they occur in 55
the several views.

On reference to the drawings it will be seen
that A is the saddle-pillar tube, to which by a
clip B and bolts F is secured the main tele-
scopic tube D. This tube D, which has a 60
tongue C locked by a bolt E in the forks b b,
(seen in the left of Fig. 5,) may be attached,
as shown, by an elbow X. This elbow may be
connected to the tube having the tongue C in its
end in any well-known way, and, as shown, its 65
diameter may be reduced and portion of it en-
ter the tube. Beneath the horizontal portion
of the telescopic tube D and taking the weight
of the same is a diagonal stay G. This stay
70 G is secured to the saddle-pillar A by a clip,
as H, and to the elbow X by insertion in a fork
on the end of X. By the aid of this diagonal
stay the angle of the umbrella with the ground,
in addition to the adjustment offered by the 75
ridge and groove in the umbrella-rod joint
hereinafter described, may be varied, since
the clip H may be moved up and down the
tube A to suit the convenience or height of
any rider. Around the top of the elbow X,
80 which portion is split, is a nut K, having a
taper-thread inside it, which when tightened
down closes the top of the elbow X and locks
the tube D. Around the top of D is attached
a taper-threaded ring I, which, with the tube
inside it, is cut in two or more places, as at J. 85
Around this taper-thread is a nut K', (with
flats or slots or other suitable means of rota-
tion,) which nut (similar to the one before
described) when screwed downwardly closes
the cuts together and locks the subsidiary 90
telescopic tube L. On the top of the tube
L is a T-piece M, at either end of which is at-
tached nuts K² and K³, having the same ob-
jects as the nut K. Through the piece M passes
the telescopic umbrella-rod N, which, as seen 95
at Fig. 2, is provided with a fork upon its
plugged end. One of these forks—say O—
may be hinged or loosely connected to the
plug in N, and on its inside face are grooves,
such as P. Into one of these enters the ridge 100
Q on the tongue-piece R, which forms part
of the plugged end of the umbrella-rod end

S. Through the side O and the tongue R passes a screw T, which is threaded into the opposite side to the side O, and when tightened up locks the rods S and N together quite rigidly.

The runner on the umbrella-rod, to which the umbrella-ribs are connected, has a slot in it to clear the head of the screw T, which can be operated by any class of spanner which may be desirable, or a thumb-nut may be employed which will clear the runner, as before described.

When the umbrella is required for use without the bicycle, a handle—such as U, Fig. 4—15 is provided. This may be of wood or any other material, and has sunk within it a metallic bush V, locked by a plug, as W, and having a threaded central hole. This handle, which may be made most ornamental, is 20 screwed on or off the threaded end of the plug in N, as occasion may require, and renders the umbrella usable for any purpose.

If an ordinary umbrella be used without any specially-constructed rod, the end of the 25 tube N may be provided with any well-known means by which the umbrella may be either attached or detached with the greatest of ease and expedition.

The method of applying my attachment to 30 a machine is as follows: The clip B being upon the main tube D and its height arranged, the bolts F are then tightened up, thereby locking it to the tube A. The clip H at the bottom of the backstay G is then tightened 35 around the tube A in the same way and in such a position that the desired angle of the umbrella with the ground is obtained. The telescopic tube D is then inserted into the elbow X and the tube L into the rod D, and 40 both of them are locked at any desired height by the lock-nuts K. Through the T-piece M (the handle U being removed) is then pushed the umbrella-rod N, which can be locked to any degree of extension by the lock-nuts K. 45 If the umbrella-rod end S is not in its place, its tongue R is then inserted between the side forks on N, and the ridge-piece entering into one of the grooves P the screw T is tightened up. The ornamental handle U may then be 50 screwed in place, and the cyclist is thus provided with a machine attachment which enables a ride to be obtained with both safety and comfort, let the weather be as inclement as it may.

55 Having now described my invention, what

I claim as new, and desire to secure by Letters Patent, is—

1. An umbrella for a cycle comprising in its construction a vertically-adjustable umbrella-support of approximately U shape, 60 which is attached at its lower end to the saddle-supporting rod of a cycle out of the way of the rider, the outer end of the upper horizontal portion being provided with a plug having a forked end, each wall of which is provided with a transverse opening and one wall is provided on its inner face with radial grooves, an umbrella proper having a rod provided with a ridge, which latter is adapted to be inserted into any one of the radial grooves 65 on the fork, and a screw passing through the openings in the fork for tightening the fork upon the umbrella-rod, and holding the umbrella at the desired angle, substantially as described.

2. An umbrella-support for a cycle which is capable of being adjusted to different heights on the frame of the cycle and which is also capable of having a tilting movement backward and forward, means for adjusting the 80 same and securing it in an adjusted position, said support being pivotally attached to the saddle-supporting rod of a cycle by means of a clip vertically adjustable thereon, and a diagonal brace-rod attached at its upper end to 85 the umbrella-support and at its lower end by a pivotal connection to a clip which is also vertically adjustable on the saddle-supporting rod, substantially as described.

3. An umbrella for a cycle comprising in 90 its construction a vertically-adjustable and backward and forward tilting support, means for adjusting the same and securing it in an adjusted position, said support being pivotally attached to the saddle-supporting rod of 95 a cycle by means of a vertically-adjustable clip and a diagonal brace-rod attached at its upper end to the umbrella-support and at its lower end by a pivotal connection to a vertically-adjustable clip on the saddle-supporting 100 rod, and means for tilting the umbrella proper to the desired extent, and holding it in such tilted position, substantially as described.

In witness whereof I have hereunto set my hand in presence of two witnesses.

ARTHUR THOMAS WOODWARD.
